CLAIM

The ornamental design for a heating equipment, as shown and described.

DESCRIPTION

FIG. 1 is a front elevational view of a heating equipment showing my new design;

FIG. 2 is a rear elevational view thereof;

FIG. 3 is a bottom plan view thereof;

FIG. 4 is a right side view thereof; and,

FIG. 5 is a perspective view thereof.

The broken lines shown form no part of the claimed design. In the drawings, the broken lines depict environmental subject matter only and form no part of the claimed design.
